TUMBLING MACHINE

John Enos Veturino, Fairhaven, Mass., assignor
to Continental Machinery Co., Inc., New Bedford,
Mass., a corporation of Massachusetts

Application April 18, 1941, Serial No. 389,633

29 Claims. (Cl. 68—27)

The present invention relates to tumbling machines, and more particularly to machines for tumbling hides, skins, fabrics and the like during degreasing, washing or otherwise treating the same.

The hides, skins, laundry or other material are ordinarily introduced into the inner cylinders of machines of the above-described character, and removed therefrom, by hand. Tools have been used from time to time for lengthening the reach of a man's arm into the cylinder, but they have not usually been satisfactory.

An object of the invention is to provide a new and improved automatically unloading mechanism, particularly for use with an open-ended machine.

With this object in view, a feature of the invention contemplates the provision of a new and improved chute that may be removably inserted into the inner cylinder of the machine, at the end of the operation of treating the contents thereof, to enable discharging or unloading the contents.

Other and further objects will be explained hereinafter and will be particularly pointed out in the appended claims.

The invention will now be more fully described in connection with the accompanying drawings, in which Fig. 1 is a view, partly in side elevation, partly in vertical longitudinal section, and partly in transverse section, of a tumbling machine of the above-described character, the longitudinal section being taken upon the line 1—1 of Fig. 2, looking in the direction of the arrows, the chute being removed, and the end doors of the inner cylinders being shown closed; Fig. 2 is a vertical transverse section taken upon the line 2—2 of Fig. 1, looking in the direction of the arrows, also with the chute removed; Fig. 3 is an end elevation of one of the inner cylinders or drums, the view being taken from the open end of the cylinder, and showing the removable chute in place above the goods contained in the cylinder; Figs. 4 and 5 are respectively side and end elevations of the preferred chute; Fig. 6 is a view similar to Fig. 3, but showing the chute commencing its unloading operation; Fig. 7 is a view of a detail, upon a larger scale, showing the small end of the chute held in place; Fig. 8 is a view similar to Figs. 3 and 6, showing the chute in its final unloading position, with the contents of the cylinder sliding from the chute into a truck, illustrated in dotted lines; Fig. 9 is a fragmentary longitudinal section similar to Fig. 1, taken upon the line 9—9 of Fig. 8, looking in

the direction of the arrows, with the chute in place, in a position corresponding to that of Fig. 8, showing the contents of the cylinder sliding through the opening in the outer end wall thereof into the truck; and Figs. 10, 11 and 12 are views, upon a larger scale, of details of the machine illustrated in Fig. 1.

As in application, Serial No. 281,255, filed June 26, 1939, now Patent 2,360,377, entitled "Washing machine," of which the present application is a continuation-in-part, a machine is shown, provided with an upright outer closed, stationary, generally cylindrical, casing or housing having a centrally disposed section 10, bounded by oppositely disposed end walls 16 and 17. Axially aligned cylindrical end-section chambers 5 and 6 for containing a washing, degreasing or other fluid are disposed at the respective ends of the centrally disposed section, the end-section chamber 6 beyond the wall 16 and the end-section chamber 5 beyond the wall 17.

The walls 16 and 17 are respectively secured to the end sections 6 and 5. Circular or cylindrical angle-iron reinforcing rings or bands 11, 25 L-shaped in cross section, are welded throughout to the respective walls 16 and 17 of the end sections 5 and 6, in axially aligned relation thereto. Gaskets (not shown) may be interposed between the iron rings 11 and the walls 16 and 17, respectively, to render the joints tight. Circular or annular bolting-ring members 202 are welded along their inside edges to the inner surfaces of the centrally disposed section 10. Weld joints are shown in the drawings black.

The centrally disposed section 10 is illustrated as further provided with a lower side-segment portion 12, of rectangular cross-section, that is secured, in any desired way, as by welding, to a base 15 by which the centrally disposed section 10 is thus directly supported. The side segment 12 is secured, as by welding 4, to the annular members 202 which, in turn, support the side walls 16 and 17. The end sections 5 and 6 are supported directly by portions 14 and 13, respectively, that slantingly project outwardly up from the base 15. The end sections 5 and 6 are further indirectly supported, however, by machine screws or bolts 9 and 8 that, extending into the bolting-ring members 202, secure them to the centrally disposed section 10.

The wall 16 is shown carrying a bearing 31 and the wall 17 a bearing 32. The bearings 31 and 32 are oppositely disposed in the centrally disposed section 10 coaxially with the cylindrical sections 6, 10 and 5. A shaft 29 is hori-

zontally journaled in the bearing 31, on and to one side of the centrally disposed housing section 10, and a shaft 30, alined with the shaft 29, is journaled in the bearing 32, on and to the other side of the centrally disposed housing section 10. The inner ends of the shafts 29 and 30 are adjacently disposed, as shown more particularly in Fig. 1, and their outer ends project through sealed openings in the walls 16 and 17, respectively beyond these walls, into the respective end sections 5 and 6.

Inner perforated tumbling drums or cylinders 18 and 19, for containing materials to be washed, degreased or the like, are respectively fixed to the outer ends of the shafts 29 and 30. The cylinder 18 is thus axially journaled to rotate with the shaft 29 in the end section 6 of the housing, and the cylinder 19 is axially journaled to rotate with the shaft 30 in the end section 5 of the housing. The cylinders are thus axially alined, and each is provided with an inner end wall 39 and an outer end wall 40. As will be more fully explained hereinafter, the outer ends of the shafts 29 and 30 are fixed to the respective cylinders 18 and 19 at their inner end walls 39.

The inner end of the shaft 29 is shown in Fig. 1 disposed within a split hub 23. The inner end of the shaft 30 is similarly shown disposed within another split hub 28 that is alined with the first-named split hub 23. The alined split hubs 23 and 28 are secured together into a unitary hub structure by means of bolts passing through pairs of alined bolt openings 25, one opening 25 of each pair in each of the split hubs 23 and 28. After the alined shafts 29 and 30 have been mounted in this unitary split-hub structure 23, 28, with their inner ends adjacently disposed, they are securely fastened therein in any desired manner, as by means of bolts extending through alined bolt openings 47 in the ends of the respective split hubs 23 and 28. To guard against accidental rotation of the shafts 29 and 30 in the hubs 23 and 28, a key 7 may be inserted in splines 37 in the shafts and corresponding splines 2 in the hubs.

The shafts 29 and 30 become thus rigidly coupled together intermediately between the cylinders 18 and 19 to rotate as a unitary shaft in the bearings 31 and 32, which bearings serve, in effect, as a single or unitary bearing structure for this unitary shaft 29, 30. The advantage of using two shafts 29 and 30, instead of only a single shaft, is to facilitate disassembly, for purposes of repair. The rotation of the shaft 29, 30 may be effected by means of a driving gear wheel 27 that is fixed to the unitary-hub structure 23, 28 so as to rotate between the bearings 31 and 32. The gear 27 is shown as driven from an electric motor 21, mounted upon a non-cylindrical upper portion 20 of the centrally disposed housing section 10. Through belts 22, the motor 21 drives a pinion 26 that, mounted upon a drive shaft 24, meshes with the gear 27.

Rotation of the driving gear 27 by the motor 21 is thus communicated, through the unitary shaft 29, 30, to the inner cylinders 18 and 19, which are thus likewise rotated in unison. The machine is thus in perfect balance, each cylinder 18 or 19 serving as a counterweight for the other. It is not necessary, therefore, to supply the outer end walls 40 of the cylinders 18 and 19 with bearing shafts, or the outer walls of the end sections 5 and 6 with bearings for such shafts, and this even though the cylinders may be of considerable size, say, sufficiently large

to carry a load of from seven hundred to a thousand pounds each. It is accordingly possible to provide these outer walls 40 each with an axially disposed circular discharge opening 41, and the outer walls of the end sections 5 and 6 each with a concentrically disposed axially alined discharge opening 42. The hides, skins, laundry and the like may be inserted into the respective cylinders 18 and 19, and removed therefrom, through the two pairs of alined registering openings or orifices 42 and 41. The washing, degreasing or other fluid in the end sections 5 and 6 may enter the cylinders 18 and 19 through their perforations and through their openings 41.

Each opening 42 may be closed, during the operation of the machine, when the contents of the cylinders are tumbled, by a frusto-conical door 44, hinged at one side, and provided with means for holding it securely in place at its other side. An annular projection in each opening 42 is adapted to engage a compressible ring seal 60 that is disposed in a circular recess in each door 44. Each door 44 is provided, along its periphery, with a cylindrical projection 61 that, when the door is closed, is disposed in a cylindrical projection 58 mounted correspondingly along the periphery of the corresponding opening 41.

In order that the cylinders 18 and 19 may be enabled the better to carry the heavy loads contained therein, without destroying their balance, and without the necessity for employing any additional bearings at the outer ends of the cylinders, it is desirable to reinforce their inner end walls 39. As these end walls 39 are duplicates, it will suffice to describe one only. According to the specific embodiment of the invention that is illustrated and described herein, each end wall 39 is reinforced by a circular spider 100 that is held securely thereagainst by rivets 101. This spider comprises radially disposed reinforcing T-beams 102 that are welded at their outer ends to the inner walls of an outer ring 104 and at their inner ends to the outer walls of a concentrically disposed inner bushing 106. The T-beams are shown in Fig. 1 adjacent to walls 39. Six such T-beams may be employed, with adjacently disposed T-beams reinforced by connecting L-beams. The bushing 106 is welded to the inner ends of the T-beams 102, both directly, and also through the medium of an annulus 110. Radially disposed lugs or fins 113 are welded to the T-beams 102 at the faces thereof, opposite to the faces that carry the legs of the T's, and also to the outer surface of the bushing 106. The lugs 113 are shown in elevation in Fig. 1. The shafts 29 and 30 are shown each extending through two annuli 124 and 126 that are welded to the inner walls of the respective bushings 106.

The outer end of each bushing 106 extends into an inset or re-entrant portion 112 of the wall 39 that is shaped frusto-conically to receive the fins 113. The smaller base of the frustum is flat to receive the outer end of the bushing 106 and the abutting outer end of the shaft 29 or 30 that is disposed therein, as hereinafter more fully described. A fitting 128, provided with a longitudinally extending opening, for cooperating with an unloading chute, as hereinafter more fully described, extends through an opening in the smaller flat base of the re-entrant frustum portion 112 and into the outer end of the shaft 29 or 30.

The inner end of the bushing 106 is secured, as by welding, to an annulus 114, to which is welded a flange 116. The inner diameter of the

flange 116 is just sufficient to receive an annulus 118 through which the shaft 29 or 30 extends, and to which the shaft 29 or 30 is secured in any desired manner, as by welding. The annulus 118 is reinforced by a number of ribs 122 which may be welded both to the shaft 29 or 30 and the annulus 118. The annulus 118 is detachably fastened to the annulus 114 in any suitable manner, as by means of machine screws or bolts 120. This detachability enables the parts to be readily separated, as for purposes of repair.

To disassemble the machine, the screws or bolts 8 and 9 are first removed. This makes it possible to remove the end sections 6 and 5 from the central section 10, leaving the cylinders 18 and 19 intact on their shafts. It is necessary also to unbolt the split-hub structure 23, 28. Access to the central section 10 may be obtained, for this purpose, through doors 200. The cylinder 18 and the shaft 29 upon which it is mounted may then be removed by pulling to the left, as viewed in Fig. 1. The cylinder 19 and the shaft 30 upon which it is mounted may similarly be removed by pulling to the right. Unscrewing of the bolts or screws 120 will make it possible to detach the shaft 29 and its annulus 118 from the cylinder 18.

A bushing 36, disposed centrally of each of the walls 16 and 17, is rigidly secured thereto at its inner end, as by welding. An inwardly projecting annulus 35 is shown welded to the inner end of the bushing 36. The bearings 31 and 32 are each provided with a bushing 129, for housing bearing rollers 131, and each having a flange 130 that abuts against an annulus 35. The flanges 130 are detachably secured to the annuli 35 in any desired manner, as by means of bolts or screws 132. The manner in which the bearings are sealed is substantially the same as disclosed in the said application. The purpose of the seals, which are of circular shape, as shown, and are pressed into their respective housings, is to retain the grease and exclude dirt and other matter from the bearings. Each seal comprises a steel outer casing 206, an annular leather ring 208, and a steel spring 210 for maintaining a constant pressure of the leather against the shaft. The leather ring 208 is so constructed that the seals act also as stuffing boxes to prevent the entrance of air during the hereinafter-described evacuation process. The end walls 16 and 17 of the centrally disposed section 10 are shown reinforced by means of webs 33 and 34 that respectively radiate from the bearings 31 and 32.

It is customary, in machines of this character, to provide more or less equally spaced, longitudinally disposed, cleats, shelves or baffles that project a short distance interiorly into the inner cylinders from the cylindrical walls thereof. The baffles, preferably of U-shaped cross-section, are illustrated as of alternately large and small size, the large-size baffles 142 projecting into the cylinder a greater distance than the small-size baffles 144. Each large baffle 142 is disposed diametrically opposite to a small baffle 144.

Let it be assumed that a large baffle 142 occupies its lowermost position. In this position, it will be effective to raise a load of skins, hides or laundry at the bottom of the cylinder. During the rotation of the cylinders by the motor 21, say, anticlockwise, as viewed in Fig. 2, this large baffle 142 will ride up along the right-hand wall of the cylinder to engage the skins, laundry or other contents thereof. As it engages them, it

will raise them up, carrying them around along the inside of the cylinder. After they have risen to a height determined by the speed of the machine and the size of the baffles, they will drop back toward the bottom of the cylinder, on to the next adjacently disposed smaller baffle 144. This results in tumbling the skins or the laundry, as a consequence of which they become intimately admixed with different portions of the liquid contained therein.

Steam may be supplied to the liquid contained in the end sections 5 and 6, for heating the contents of the cylinders 18 and 19, through steam-inlet conduits or pipes 133 that are connected to heating jackets 134 and 136. The jacket 134 is shown provided upon the lower portion of the end section 6 and the jacket 136 on the lower portion of the end section 5. The jackets 134 and 136 are shown provided with drains 204.

The lower end of each of the walls 16 and 17 is provided with a shelf 65, supported by an upstanding projection 66. One of the projections 66 is welded to one end of a lower wall 68, shown constituted of the upper wall of a cylindrical chamber 184. An L-shaped flange member 70 is welded to the other end of the wall 68. The L-shaped member 70 may be secured to the other projection 66 by bolts or the like 69, that may be removed for purposes of disassembly. A duct chamber 180 is thus provided under the right-hand shelf 65, and to the right of the right-hand projection 66, as viewed in Fig. 1, and a duct chamber 182 is similarly provided under the left-hand shelf 65, and to the left of the left-hand projection 66. The chambers 180 and 182 are in the form of rectangular boxes, welded in place in suitable openings of the walls 16 and 17. The outer vertical side walls of the chambers 180 and 182 are shown at 212, the inner vertical walls are shown at 65, their upper walls are provided by the shelves 65, and a continuous lower wall of the chambers is shown at 214. The chamber 180 communicates with the end section 5, the chamber 182 communicates with the end section 6, and the chambers 180 and 182 communicate with each other through the cylindrical chamber 184. The chamber 184 is in the form of a circular pipe, welded, as before explained, in a wall opening of the chamber 180, and bolted to a wall opening in the chamber 182. The chamber 180 is connected with an outlet water drain or evacuating line 186 shown disposed laterally of the casing 10, adjacent to the bottom thereof, and the chamber 182 with a solvent drain 188 for both end sections. The chambers thus serve as a drain; and also to equalize the level of the liquids in the sections 5 and 6.

Water may be supplied to the end sections 5 and 6 through a water-inlet pipe 190, and the solvent and the emulsifier through a solvent-inlet pipe 192.

After the end sections 5 and 6 have been filled to the desired level, the skins or hides are tumbled by rotating the gear 21, to rotate the cylinders in their respective end sections, as before described.

After the hides or skins have been thus tumbled, and after the water and solvents contained in the end sections 5 and 6 have been drained, it is found advantageous to subject the hides or skins to the action of a vacuum. This may be effected, the doors 44 being closed at this time, by pumping out the air. The air may be pumped out of the end section 5 through a pipe 194 and out of the

end section 6 through a pipe 196. Under the action of this vacuum, the solvent is readily extracted from the hides or skins, the closed end sections 5 and 6 at this time constituting a drying chamber. As the hides or skins become cooled, in consequence, it may be desirable to add further heat during the evacuation, as by supplying steam to the jackets 134 and 136, or by introducing hot water into the end sections 5 and 6. One should be careful, however, not to supply so much heat as to injure the skins or hides. During this evacuating operation, the cylinders may be rotated, if desired; preferably, as during the tumbling, in the same direction continuously.

The vacuum in the end sections 5 and 6 may later be broken by admitting air through an air inlet valve 198.

The size of the cylinders, in machines of this character, has heretofore been restricted, among other reasons, by the fact that their unloading has been performed manually. A workman can not reach with his arm very far into the cylinder to remove the contents thereof. According to the present invention, however, provision is made for unloading the cylinders automatically. This makes it possible to increase materially the size of the machine.

This unloading is effected with the aid of a novel removable unloading chute 47. The chute is more or less funnel- or cone-shaped, having surfaces angulated with respect to the axis of the cylinder, and its axis substantially aligned with the axis of the cylinder. In its preferred form, the funnel or cone is not circular in cross-section; the cross-section is of varying curvature. The curvature is sharper or greater along the bounding side element 158 than along the opposite bounding side element 160, and is of least sharpness in between; that is, the smallest radius of curvature is along the element 158, a larger radius of curvature along the element 160, and still larger radii of curvature in between. As clearly appears from the drawings, however, the radii of curvature are not the same at all points of the elements 158 and 160 and in between. For example, the radius of curvature at the end of the element 158 bounded by the smaller end 162 of the cone is smaller than the radius of curvature at the outer edge 166. Also, the radius of curvature at the end of the element 160 bounded by the smaller end 162 is less than the radius at the outer edge 166. For any cross section, however, the radius of curvature is least adjacent to the element 158 greater adjacent to the element 160, and greatest in between.

This construction renders the chute flatter in between the bounding side elements 158 and 160 than at these bounding elements. The chute is provided with a longitudinally disposed lip or shelf 163 along the bounding side element 160, for engaging a baffle 142, as presently to be described.

The smaller end 162 of the cone is provided with a perforated ear 53 that is adapted to be aligned with the before-mentioned opening in the perforated plug 128. A pin 164, inserted through the perforated ear 53 and into the opening in the plug 128 at the axially inner end of the cylinder, will hold the chute in place in the cylinder, with the larger end 166 of the chute disposed in the opening 41 and engagingly supported by the lower wall of the opening 41. Though thus held in place by the pin 164 and the said lower wall of the open-

ing 41, so as to rotate with the cylinder, the chute is free to rotate axially of the cylinder about the pin 164. The concave side of the chute, when the chute is thus held in position by the pin 164, slopes or slants or tapers downward in an axially outward direction from the axially inner end of each cylinder near the ear 53, toward the discharge openings 41 and 42.

Upon the completion of the treatment of the materials contained in the cylinders 18 and 19, the motor 21 is stopped, and the doors 44 are opened. The unloading chute 47, which is normally outside the cylinder during the tumbling operation, in order not to interfere with the tumbling, is then removably inserted into each cylinder through the openings 41 and 42, in the space above the contents of the cylinders, with the convex side of the chute upward, as illustrated in Fig. 3. The pin 164 is inserted through the opening in the ear 53, and the motor 21 is restarted. The shelf 163, it will be noted, is shorter, at the shoulder 165, than the bounding side 160, in order that the outer edge 166 of the chute may extend through the openings 41 and 42, while the shelf 163 is entirely within the cylinder, in engagement with a baffle 142.

As the cylinder rotates, anti-clockwise, as viewed in Figs. 3, 6 and 8, the lip or shelf 163 will at first rotate through a part revolution past a small baffle 144. It will, however, soon engage a large baffle 142. It rotates past this small baffle 144 because the lip or shelf 163 on the chute 47 is just long enough to engage with this baffle 142, which is considerably longer than the baffle 144. After this engagement with the large baffle 142, the chute 47 will rotate with the cylinder. In Fig. 3, the lip or shelf 163 is shown previously positioned in engagement with a large baffle 142. The engagement of the baffle 142 by the shelf 163 will prevent further rotation of the chute with respect to the cylinder. During the further anti-clockwise rotation of the cylinder by the motor 21, therefore, the chute will be actuated, concave side forward, into the contents of the cylinder. The edge 158 is shown entering into the contents of the cylinder in Fig. 6. The contents in the interior of the cylinder, therefore, becoming thus loaded on to the concave side of the chute, will be directed or conveyed gravitationally by the chute, during its further rotation with the rotation of its cylinder, toward the openings 41 and 42, as illustrated in Figs. 8 and 9. In the course of a fraction of a revolution of the cylinders 18 and 19, their contents will slide down along the chute 47, through the openings 41 and 42, and into a truck 52 that may be positioned adjacent to these openings 41 and 42.

After the cylinders have become thus automatically unloaded, the chutes may be removed therefrom, and the machine prepared for another operation.

It will be obvious that, since the cylinders 18 and 19 rotate as a unit, it will be necessary to use right-hand and left-hand chutes in the respective cylinders. One of these is shown in Figs. 3, 6 and 9 in the cylinder 19. If the chute shown in Fig. 9 were used in the cylinder 18, obviously its convex side would be downward in Fig. 3, instead of its concave side, as illustrated.

Modifications will occur to persons skilled in the art, and all such are considered to fall within the spirit and scope of the invention, as defined in the appended claims.

What is claimed is:

1. A machine of the character described having, in combination, a cylinder interiorly provided with a baffle and having an end wall provided with an opening, means for actuating the cylinder, and means movable with respect to the cylinder and engageable with the baffle during such movement for directing the contents of the cylinder toward the opening.

2. A chute having a relatively small end, a relatively large end, and bounding sides connecting the ends, the chute being provided at its relatively small end with an ear and having a lip along one of its bounding sides.

3. A machine of the character described having, in combination, a cylinder having two end walls one of which is provided with an opening, means for rotating the cylinder axially of the end walls, a chute for unloading the cylinder, the chute having a relatively small end and a relatively large end, and means for securing the chute in the cylinder with the relatively small end attached to the other end wall.

4. A machine of the character described having, in combination, a rotatable shaft, means for rotating the shaft, a cylinder having a baffle and end walls one of which is provided with an opening, the cylinder being fixed to the shaft at the other end wall, a chute, and means for mounting the chute in the cylinder so that it is free to rotate relative to the cylinder, the chute having a lip for engaging the baffle during the rotation of the cylinder to prevent its further rotation relative to the cylinder, thereby to enable the chute to unload the cylinder.

5. A machine of the character described having, in combination, a casing having a centrally disposed section and an end section disposed at each end of the centrally disposed section, a bearing disposed in the centrally disposed section, a rotatable shaft journaled in the bearing with its ends projecting beyond the bearing, means supported by the centrally disposed section for rotating the shaft, a cylinder disposed in each end section, the cylinders each having two end walls one of which is open, the cylinders being fixed to the respective ends of the shaft at the other end walls to rotate with the shaft in the respective end sections, and removable right-hand and left-hand chutes disposed in the respective cylinders and rotatable with the cylinders for unloading the respective cylinders.

6. A washing machine comprising a housing, a horizontal shaft journalled on and extending at one side of said housing, motor means on said housing connected to turn said shaft, and a washing cylinder carried by said shaft at said side of the housing, said cylinder having a substantially axial washing-discharge opening in its outer end, said cylinder having therein chute means for feeding the washing in said cylinder toward said discharge opening, said chute means comprising a body having at least one concave side slanting from the axially inward end of said cylinder toward said discharge opening, said concave side being arranged to receive the washing present in the cylinder and convey the washing gravitationally toward said discharge opening, said concave slide having means at one end to supportably connect with a part on the axially inner end of said cylinder, and said concave side having further means on its opposite end to supportably engage a part of the wall of said discharge opening to position said concave slide

to deliver washing thereon through said discharge opening.

7. A tumbling machine having, in combination, a casing for containing a fluid, the casing having an end wall provided with an opening, a tumbling container in the casing into which some of the fluid may enter, the container having adjacent to the casing end wall an end wall provided with an opening alined with the casing-

10 end-wall opening, means for actuating the container in the casing to tumble the contents of the container in the fluid, a door for closing the casing-end-wall opening during the tumbling of the said contents, and means actuatable with the container for directing the contents of the container toward the alined end-wall openings.

8. A tumbling machine having, in combination, a tumbling container having an end wall provided with an opening, means for actuating the container to tumble the contents thereof, and unloading means insertable into the container through the opening after the tumbling operation and actuatable thereafter with the container for directing the contents of the container toward the opening to unload the container, the unloading means being normally outside the container during the tumbling operation in order not to interfere with the tumbling.

9. A tumbling machine having, in combination, a tumbling container having an end wall provided with an opening, means for actuating the container to tumble the contents thereof, and a chute insertable into the container through the opening after the tumbling operation and actuatable thereafter with the container for directing the contents of the container toward the opening to unload the container, the chute being normally outside the container during the tumbling operation in order not to interfere with the tumbling.

10. A tumbling machine of the character described having, in combination, a tumbling container interiorly provided with a baffle and having an end wall provided with an opening, means for actuating the container to tumble the contents thereof, and means insertable into the container after the tumbling operation and engageable with the baffle and actuatable thereafter with the container for directing the contents of the container toward the opening.

11. A tumbling machine having, in combination, a casing having an end wall provided with an opening, a tumbling container in the casing having adjacent to the casing end wall an end wall provided with an opening alined with the casing-end-wall opening, means for actuating the container in the casing to tumble the contents of the container, and means insertable into the container after the tumbling operation and actuatable thereafter with the container for directing the contents of the container toward the alined end-wall openings.

12. A machine of the character described having, in combination, substantially alined containers each having an outer end wall provided with an opening, means for actuating the containers, and right-hand and left-hand chutes disposed in the respective containers and actuatable with the containers for directing the contents of the containers toward the respective openings.

13. A washing machine comprising a casing for containing a washing fluid, a washing cylinder rotatably mounted in said casing and into which some of the washing fluid may enter, means for rotating the cylinder in the casing to wash the

contents of the cylinder in the washing fluid, said cylinder having a discharge opening in an end thereof, said casing being formed with a discharge orifice registered with said discharge opening, and a chute mounted within and rotatable with said washing cylinder, said chute having surfaces angulated with respect to the axis of said cylinder for moving the contents of the cylinder after washing through said opening and said orifice as the cylinder is rotated.

14. A washing machine comprising a housing for containing a washing fluid, a horizontal shaft journalled on and extending at one side of said housing, a washing cylinder carried by said shaft at said side of the housing and into which some of the washing fluid may enter, and motor means on said housing connected to turn said shaft in order to rotate the cylinder in the housing to wash the contents of the cylinder in the washing fluid, said cylinder having a substantially axial washing-discharge opening in its axially outer end, and said cylinder having therein chute means rotatable therewith for feeding the contents of said cylinder after washing toward said discharge opening.

15. A washing machine comprising a housing for containing a washing fluid, a horizontal shaft journalled on and extending at one side of said housing, a washing cylinder carried by said shaft at said side of the housing and into which some of the washing fluid may enter, and motor means on said housing connected to turn said shaft in order to rotate the cylinder in the housing to wash the contents of the cylinder in the washing fluid, said cylinder having a substantially axial washing discharge opening in its axially outer end, said cylinder having therein chute means rotatable therewith for feeding the contents of said cylinder after washing toward said discharge opening, said chute means comprising a body having at least one concave side slanting from the axially inner end of said cylinder toward said discharge opening, and said concave side being arranged to receive the washing present in the cylinder and convey the washing gravitationally toward said discharge opening.

16. A washing machine comprising a housing for containing a washing fluid, a horizontal shaft journalled on and extending at one side of said housing, a washing cylinder carried by said shaft at said side of the housing and into which some of the washing fluid may enter, and motor means on said housing connected to turn said shaft in order to rotate the cylinder in the housing to wash the contents of the cylinder in the washing fluid, said cylinder having a substantially axial washing-discharge opening in its axially outer end, said cylinder having therein chute means rotatable therewith for feeding the contents of said cylinder after washing toward said discharge opening, said chute means comprising a substantially conical body having its smaller end connected to the axially inner end of said cylinder and with its axis substantially aligned with the axis of said cylinder, and the body having a concave side to receive washing from the interior of said cylinder and convey said wash toward said discharge opening.

17. A washing machine comprising a casing for containing a washing fluid, a washing cylinder supported for rotation in the casing and into which some of the washing fluid may enter, drive means operatively connected to said washing cylinder for rotating said washing cylinder in the casing to wash the contents of the cylinder in

the washing fluid, the axially outer end of said washing cylinder being formed with a wash-discharge opening aligned with a discharge orifice provided in the end wall of the casing, chute means within the washing cylinder for moving the contents of the cylinder after washing through said discharge opening and orifice to empty the washing cylinder of the contents thereof after washing, said chute means comprising a body mounted axially in said cylinder and having a concave chute area slanting in an axially outward direction toward the discharge opening of the cylinder, and means for securing said chute in said cylinder.

18. A tumbling machine having, in combination, a tumbling container interiorly provided with a baffle and having an end wall provided with an opening, means for actuating the container to tumble the contents thereof, and a chute insertable into the container after the tumbling operation having a portion engageable with the baffle and actuatable thereafter with the container for directing the contents of the container toward the opening.

19. A tumbling machine having, in combination, a casing having a centrally disposed section and an end section disposed at each end of the centrally disposed section, the end sections being adapted to contain a fluid and each having an outer wall provided with an opening, a tumbling cylinder in each end section into which some of the fluid may enter, each cylinder having adjacent to the corresponding casing end wall an end wall provided with an opening aligned with the corresponding casing-end-wall opening, means disposed in the central section for rotating the cylinders in the respective end sections to tumble the contents of the cylinders in the fluid, and right-and-left-hand chutes disposed in the respective cylinders and rotatable with the cylinders for respectively directing the contents of the cylinders toward the aligned end-wall openings of the respective end sections and the cylinders contained therein to unload the respective cylinders.

20. A washing machine comprising a casing comprising a central section and end sections secured to opposite ends of said central section, a washing cylinder in each of said end sections, a shaft journalled in the end walls of said central section and on which said cylinders are supportably mounted, and drive means on said central section and operatively connected to said shaft for simultaneously rotating said washing cylinders, the axially outer ends of said washing cylinders being formed with wash-discharge openings aligned with discharge orifices provided in the end walls of the corresponding end sections, and right-and-left-hand means within the respective washing cylinders for moving the wash therein through said discharge openings and said orifices to empty the washing cylinders of the wash therein.

21. A washing machine comprising a casing comprising a central section and end sections secured to opposite sides of said central section, a washing cylinder in each of said end sections, a shaft journalled in the end walls of said central section and on which said cylinders are supportably mounted, and drive means on said central section and operatively connected to said shaft for simultaneously rotating said washing cylinders, the axially outer ends of said washing cylinders being formed with wash-discharge openings aligned with discharge orifices provided in the end

walls of the corresponding end sections, and right-and-left-hand chutes within the respective washing cylinders for moving the wash therein through said discharge openings and said orifices to empty the washing cylinders of the wash therein, said chute means tapering from the inner ends of the cylinders toward said discharge openings.

22. A washing machine comprising a central housing, a pair of shaft bearings on the opposite end walls of said housing, a horizontal shaft journaled through said shaft bearings, said shaft having end portions extending axially beyond the corresponding end walls of the housing, a washing cylinder supportably mounted on each of said end portions, a motor on said central housing, and drive means within said central housing and operatively connecting said motor and said horizontal shaft, said washing cylinders having laundry-discharge openings formed in their outer ends, said discharge openings being substantially axially aligned with said horizontal shaft, and right-and-left-hand concave chute means within the respective cylinders for moving the laundry toward discharge through said discharge openings.

23. A tumbling machine having, in combination, a container having an end wall provided with an opening, means for actuating the container to tumble the contents thereof, and a chute insertable into the container through the opening in the space above the contents of the container and being actuatable with the container, whereby the contents of the container will become loaded upon the chute during the actuation of the container, the chute having a surface that slopes downward toward the opening when the said contents become so loaded upon the chute, and the chute being normally outside the container during the tumbling of the contents of the container in order not to interfere with the tumbling.

24. A tumbling machine having, in combination, a container having an end wall provided with an opening, means for actuating the container to tumble the contents thereof, a chute insertable into the container through the opening in the space above the contents of the container, and means for rotating the chute into the contents of the container through a part-revolution to cause the contents of the container to become deposited upon the chute, the chute having a surface that slopes downward toward the opening when the said contents become so deposited upon the chute, and the chute being normally outside the container during the tumbling of the contents of the container in order not to interfere with the tumbling.

25. A tumbling machine having, in combination, a tumbling container having two oppositely disposed end walls one of which is provided with an opening, means for actuating the container to tumble the contents thereof, a chute for unloading the container through the opening insertable into the container through the opening, the chute having a relatively small end, a relatively large end, and bounding sides connecting the ends, and means for securing the chute in the container with the relatively small end secured to the other end wall.

26. A tumbling machine having, in combination, a container having an end wall provided with an opening, means for actuating the container to tumble the contents thereof, a door for closing the end-wall opening during the tumbling of the said contents, and means insertable in the container through the opening after the tumbling operation and actuatable with the container for directing the contents of the container toward the opening.

27. A tumbling machine having, in combination, a casing for containing a fluid, the casing having an end wall provided with an opening, a tumbling container in the casing into which some of the fluid may enter, the container having adjacent to the casing end wall an end wall provided with an opening aligned with the casing-end-wall opening, means for actuating the container in the casing to tumble the contents of the container in the fluid, and a chute for directing the contents of the container toward the aligned end-wall openings.

28. A tumbling machine having, in combination, a tumbling container having an inner end wall and an outer end wall provided with an opening, means for actuating the container to tumble the contents thereof, a chute insertable into the container after the tumbling operation and actuatable thereafter with the container for directing the contents of the container toward the opening, and means for detachably securing the chute to the inner end wall of the cylinder, the chute having a portion adapted to rest upon the wall of the opening of the outer end wall when secured to the inner end wall.

29. A tumbling machine having, in combination, a tumbling container interiorly provided with a projection and having an end wall provided with an opening, means for actuating the container to tumble the contents thereof, and a chute insertable into the container after the tumbling operation having a portion engageable with the projection and actuatable thereafter with the container for directing the contents of the container toward the opening.

JOHN E. VETORINO.
